UNITED STATES PATENT OFFICE.

CESARE LAURENTI, OF SPEZIA, ITALY, ASSIGNOR TO SOCIETÀ FIAT SAN GIORGIO, OF SPEZIA, ITALY.

DIVING-RUDDER FOR SUBMARINE VESSELS.

1,125,567.

Specification of Letters Patent.

Patented Jan. 19, 1915.

Application filed March 21, 1914. Serial No. 826,182.

To all whom it may concern:

Be it known that I, CESARE LAURENTI, engineer, of Spezia, Italy, have invented certain new and useful Improvements in or 5 Relating to Diving-Rudders for Submarine Vessels, of which the following is a full, clear, and exact specification.

The present invention relates to improvements in diving rudders for submarine vessels and diving boats, and has for its object 10 to remove the drawbacks peculiar to the diving rudders hitherto used. These diving rudders, which project from the body of the vessel, are exposed in a high degree to 15 the resistance of the water and also to shocks from floating bodies. Even if the rudder be made flexible, the above-mentioned drawbacks, though somewhat lessened when traveling under water, are never completely 20 removed. There is also another drawback of frequent occurrence, namely, that the rudder cannot be brought quickly into the operative position at the moment when it is desired to act. Non-flexible forms of 25 diving rudder greatly increase the resistance to forward movement, even when they are situated below the water line.

According to the present invention the aforesaid drawbacks are obviated by the 30 diving rudders being formed of plane surfaces which lie close against the body of the vessel, and it is only at the moment when they are required to act that they are operated and moved outward by a device, housed 35 in the interior of the submarine vessel and causing them to swing about one of their edges, so that they form a surface which projects from the body of the vessel at an incline in relation to the direction of travel, 40 the effect of said surface being to cause the vessel to dive or rise.

In order that the invention may be more readily understood reference is made to the accompanying drawings in which:—

45 Figure 1 is an elevation of part of a submarine vessel showing the rudders closed against the sides thereof. Figs. 2 and 3 are views of the rudders. Fig. 4 is a plan of the operating mechanism for the rudders 50 and Fig. 5 is an elevation of the same.

As can be seen, the diving rudders consist of plane or stepped surfaces A, B, preferably triangular in shape. The diving rudders, which lie close against the outer skin

on the bow or stern of the vessel, are secured 55 to the same by hinges a, b, or c, d. By means of levers which engage at e or f, the diving rudders are operated from the interior. By swinging them about the edges a, b, or c, d, the diving rudders A, or B are moved outward 60 and assume a definite angle with relation to the hull. By means of the operating mechanism the diving rudders can be drawn back again until they lie close against the hull. The action of these diving rudders is therefore as follows: For diving, 65 the upper rudders A (Fig. 2) are opened out until they have attained a certain angle with relation to the hull, whereby, in consequence of the slanting position of the diving 70 rudders the bow is forced downward by the pressure of the water against the rudders as the vessel moves forward. On drawing back the rudders and opening out the rudders B (Fig. 3) a force is set up, by the forward movement of the vessel, which causes 75 the bow to rise. If the diving rudders be arranged at the after end of the vessel, the opposite effect is naturally produced.

A form of the operating mechanism is 80 shown in Figs. 4 and 5. Here 1—2 indicate a screw influenced by a tube 3, which passes through the hull of the vessel and extends as far as the steering room. A nut 4, adapted to travel along the said screw, influences 85 a lever 5 which turns about a pivot 6. A disk 7, rigidly secured to the lever 5, is provided with slots 8—9 and 9—10 on the one side and 11—12 and 12—13 on the other. The slots 9—10 and 12—13 have the central 90 point 5 of the disk as their center of curvature while the slots 8—9 and 11—12 are curved inward toward the center of the disk. In these slots engage pins 9 and 12 on the levers 9—14 and 12—17 which are 95 adapted to turn on pivots 14, 17 which belong to conical toothed sectors 15 and 20. The levers 9—14 and 12—17 are connected to other levers 16—18 and 21—22 which turn about the fixed points 18 and 22. The 100 toothed sectors 15 and 20 engage with bevel wheels 19 and 23 which are secured on the shafts 24 and 25, to which latter are connected bell crank levers 26—27 and 28—29 the ends of which are connected to rods 105 27—e' and 26—e, as also 28—f and 29—f'. The rods in question engage, at the points e, f, e', f', with the four rudders, two of

which are arranged on the right hand side and two on the left hand side of the submarine vessel.

The diving rudders are operated in the following manner: If the lever 5 and disk 7 be moved, toward the right for example, by rotating the rod 3, the pin 9 is displaced in the slot 8—10, thus operating the lever, and consequently the toothed sector 15, the movement of which is transmitted to the bevel wheel 19. In this way the shaft 24 is operated, and consequently the bell crank lever 26—27 which actuates the rods 26—e and 27—e', so that the one pair of rudders, for example the one for diving (Fig. 2) is opened out. On the lever 5 being drawn back, the two rudders close up until they again lie close against the outer skin of the submarine. If the lever 5 be displaced toward the left, the toothed sector 20 and the cone wheel 23 are operated, and consequently the bell crank lever 28—29, which moves the rods 28—f and 29—f', for the purpose of opening out the other pair of rudders with the object of causing the vessel to rise again (Fig. 3).

What I claim is:

1. A depth controlling rudder for boats pivoted along a fixed longitudinal axis 30 which is inclined to the horizontal.

2. A depth controlling rudder for boats, having one of its edges pivoted to the side of the hull at an inclination to the horizontal, said pivoted edge forming the axis on 35 which said rudder is adapted to turn, said rudder being adapted to be turned flat against the hull.

3. A boat having depth controlling rudders on each side thereof, said rudders being arranged in pairs on each side of the hull and having axes of rotation substantially in the plane of the side of the hull, and adapted to lie flat against the same, one rudder in each pair having its axis of rotation upwardly inclined and the other rudder in each pair having its axis of rotation 40 downwardly inclined, whereby, when extended, said rudders present oppositely inclined planes to the water.

tended, said rudders present oppositely inclined planes to the water.

4. A boat having depth controlling rudders on each side thereof, said rudders being arranged in pairs on each side of the hull and having axes of rotation substantially in the plane of the side of the hull, and adapted to lie flat against the same, one rudder in each pair having its axis of rotation upwardly inclined and the other rudder in each pair having its axis of rotation 45 downwardly inclined, whereby, when extended, said rudders present oppositely inclined planes to the water, and means for operating said rudders, said means being adapted to turn together rudders on both sides of the boat having similar inclination of their axes of rotation.

5. A boat having depth controlling rudders on each side thereof, said rudders being arranged in pairs on each side of the hull and having axes of rotation substantially in the plane of the side of the hull, and adapted to lie flat against the same, one rudder in each pair having its axis of rotation upwardly inclined and the other rudder in each pair having its axis of rotation 50 downwardly inclined, whereby, when extended, said rudders present oppositely inclined planes to the water, and means for operating said rudders, said means being adapted to turn together rudders on both sides of the boat having similar inclination of their axes of rotation.

In witness whereof, I have hereunto signed my name in the presence of two subscribing witnesses.

CESARE LAURENTI.
